UNITED STATES PATENT OFFICE.

ROBERT ERNEST MCFARLAND, OF CICERO, ILLINOIS, ASSIGNOR TO WESTERN ELECTRIC COMPANY, INCORPORATED, OF NEW YORK, N. Y., A CORPORATION OF NEW YORK.

BRAIDING MACHINE.

Application filed August 18, 1924. Serial No. 732,821.

This invention relates to braiding machines and more particularly to a machine for covering a core.

The electrical apparatus and switchboards 5 employed in telephone exchanges usually are interconnected by cables composed of a plurality of electrical conductors forming a core which is sheathed by a braided textile cover. In order to meet the requirements of the 10 switchboards and apparatus it is frequently advantageous to employ cables of this nature having noncircular cross sectional contours. Due to the restricted space, in some instances, it is necessary to use a cable of 15 substantially rectangular cross section the thickness of the cable being so small compared with its width that the cable is called a "flat type" cable. In braiding a cover upon a switchboard cable core of circular 20 cross section of one type it has been found advantageous from a quality and production standpoint to use what is termed five stranded or five end cotton thread, but when braiding a cover upon a substantially flat cable 25 core of the same type, which cover will have the same quality and capable of being produced at substantially the same speed, it is advantageous to use what is termed six stranded or six end cotton thread.

To use a five stranded thread in covering a flat core and produce substantially the same linear feet of braided cable per minute as compared to the circular type of core 30 would result in an open braid of poor 35 quality, since the speed of the capstan in use in covering the flat type of core is greater than when covering the circular type of core.

To operate a braiding machine using a 35 braiding head of any suitable type for braiding a cover for either a circular or flat type core, it is necessary, due to the difference in contours between these two types of cores, to change the head and capstan speeds (or R. P. M.) for each type of core to produce 40 the before mentioned results. For example, in particular instances it has been found advantageous in covering a circular core to drive the head at a speed of 141.4 R. P. M. and the capstan at a speed of 1.2745 R. P. M. to produce a cover at a linear speed of 45 6.250 feet per minute using five end cotton threads and with a flat type core the head was driven at a speed of 119.8 R. P. M. and

the capstan at a speed of 1.6167 R. P. M. to produce a cover of substantially the same 55 quality at a linear speed of 7.938 feet per minute using six end cotton threads.

Heretofore, in practice, to make the necessary changes in the driving mechanism of a braiding machine to give the above listed 60 results, it has been necessary to tear down the machine to change the gear ratio, this frequently requiring a considerable amount of time, during which the machine of course is idle.

An object of this invention is to provide a braiding machine in which the speeds of the braiding means and of the material may be readily and simultaneously varied.

Another object of this invention is to provide 70 a machine for covering a core which may be readily adapted for covering cores of different cross-sectional contours.

In accordance with the general features of the invention a braiding machine is provided 75 with a device for simultaneously and selectively changing the speeds of operation of the braiding head and the capstan to produce substantially the same quality of covering, depending upon the type of cable 80 core.

Other features and advantages of the present invention will become apparent in the following detailed description and will be particularly pointed out in the appended 85 claims.

The accompanying drawings illustrate one embodiment of the invention, in which

Fig. 1 is a fragmentary front elevation of a multi-unit braiding machine for covering 90 cable core embodying the features of the invention with standard Wardwell braiding heads shown diagrammatically;

Fig. 2 is an enlarged vertical sectional view through the speed changing device of a 95 braiding unit, showing the interconnected drive to the capstan and braiding head;

Fig. 3 is a fragmentary plan sectional view taken upon the line 3-3 of Fig. 2, showing the drive between the shaft carrying the speed changing device and the main 100 drive shaft, and

Fig. 4 is a fragmentary vertical sectional view taken upon the line 4-4 of Fig. 2 looking in the direction indicated by the 105 arrows.

As illustrated in Fig. 1 of the drawings, the invention is shown applied to a multi-unit braiding machine for covering cable core and although only two of the braiding heads are shown diagrammatically at 10 for convenience of illustration, it will be readily understood that the number may vary and also that the complete machine mounted upon a single supporting frame 11 may comprise two rows of heads 10 positioned back to back.

Mounted upon the top of the frame 11 near one end of the machine is a motor (not shown) which is suitably connected to a main drive shaft 13 which extends the entire length of the machine and which is normally rotated at a constant speed. Through suitable coupling means indicated generally by the numeral 14, and to be described in greater detail hereafter, the heads 10 and capstans 16 for drawing the covered core from the braiding heads 10 are operated at certain relative speeds, depending upon the type of core to be covered, as heretofore explained.

A supply reel 18 and a take-up reel 19 are suitably positioned side by side in line with and directly under each braiding head and near the floor line where they may be quickly and easily mounted upon or removed from their supporting or driving spindles. The take-up reel 19 is suitably driven from the before mentioned motor through means not shown.

When the machine is composed of a plurality of braiding units as illustrated in Fig. 1 of the drawings, the main drive shaft 13 is constantly driven and at each braiding unit a suitable friction clutch indicated generally by the numeral 20 (Fig. 3), is provided so that each unit may be set in operation and stopped by an operator without interfering with the other units of the machine. Suitably secured to the driven member 21 of each clutch 20 is a gear 22 which meshes with a gear 23 secured to a shoulder-jack shaft 25, journaled in bearings 26 formed in a housing 27 (Figs. 1 and 2). Keyed to rotate with the shaft 25 but longitudinally slideable thereon is a jaw clutch 28 shown in the drawings (Figs. 2 and 3) as engaging a bevel gear 29 which is free to rotate upon the shaft 25. The jaw clutch 28 upon being moved to the left as viewed in Fig. 2 is adapted to engage a bevel gear 31 affixed to a sleeve 32 free to rotate upon a reduced portion 33 of the shaft 25. Also mounted upon the sleeve 32 in a manner similar to the jaw clutch 28 and bevel gear 29 carried upon the shaft 25 is a second jaw clutch 34 and a bevel gear 35, the clutch 34 being adapted upon a movement to the left as viewed in Fig. 2 to engage a bevel gear 37 affixed to a second sleeve 39 free to rotate upon a further reduced portion 40 of

the shaft 25. The bevel gears 29 and 31 are interconnected by bevel gears 41 and 42, also the bevel gears 35 and 37 by bevel gears 43 and 44. Affixed to the sleeve 32 intermediate the bevel gears 31 and 35 is a sprocket wheel 46 connected to a second sprocket wheel 48 by a sprocket chain 49. The wheel 48 is secured to a shaft 50 which is journaled at one end in a housing 51 suspended from the housing 27 and enclosing the chain 49 and at its opposite end in a suitable bearing (not shown) for operatively connecting the shaft 50 with the braiding head 10. Secured to rotate with the sleeve 39 is a worm 55 which meshes with a worm wheel 56 secured upon a shaft 57. The rotation of the shaft 57 is transmitted to a shaft 58 which is rotated at a suitable ratio by gearing indicated generally by the numeral 59 which is operatively connected by suitable gearing (not shown) to the capstan 16. A detailed illustration and description of the gearing for connecting the shafts 50 and 58 with the braiding head 10 and capstan 16, respectively, has been omitted for the sake of simplicity, since it is not necessary to a complete understanding of the present invention.

Shifting forks for the jaw clutches 28 and 34 are indicated at 61 and 62, respectively, which are operatively connected together by a link rod 63. Suitably connected to the right hand end of the rod 63 as viewed in Fig. 2 is a vertically extending hand lever 64 which is pivotally supported intermediate its ends upon the housing 27 at 66. A suitable opening is provided in the housing 27 for the lower end of the lever 64 which extends downward to a point within easy reach of an operator (Fig. 1). Upon a movement of the hand lever 64 about its pivot 66 in a counter-clockwise direction it will readily be seen that the jaw clutches 28 and 34 will be shifted to the left thereby disengaging them from the bevel gears 29 and 35 and engaging them with the bevel gears 31 and 37, respectively.

As shown in the drawings the position of the clutch jaws 28 and 34 indicate that the machine is set for braiding a cover upon a flat type of cable core. This position of the jaws provide for driving the capstan at a relatively greater speed of operation than when working upon a circular type of cable core. At the same time provision is made for reducing the speed of operation of the braiding head relative to the required speed thereof when working upon a circular type of cable core.

The operation of this speed changing device with the clutch jaws 28 and 34 engaged for working upon a flat type of cable core as shown, is as follows:

As explained heretofore by engaging the clutch 20 with the gear 22 power is transmitted to the jack shaft 25 through the gear

23 carried thereon meshing with the gear 22 secured to the driven member 21 of the clutch 20. The rotation of the shaft 25 is transmitted through the jaw clutch 28 to the 5 bevel gear 29 mounted free upon the shaft 25, and thence through the cooperating gears 41, 42, and 31 to the sleeve 32 which has keyed thereto the sprocket wheel 46 which as heretofore described drives the 10 braiding head 10. The jaw clutch 34 being keyed to the sleeve 32 causes the rotation of the bevel gear 35 mounted free upon the sleeve 32. The rotation of the gear 35 is transmitted to the worm 55 through the operating 15 gears 43, 44, and 37 and the sleeve 39. The worm 55 through the worm wheel 56, gearing 58, and shaft 59 as heretofore described drives the capstan 16. When a circular type of cable core is to be worked 20 upon the hand lever 64 is turned about its pivot 66 in a counter-clockwise direction, which movement causes the jaw clutches 28 and 34 to be moved longitudinally upon the shaft 25 and sleeve 32, respectively, to engage 25 the bevel gears 31 and 37, respectively. With this engagement of the jaw clutches power is transmitted from the shaft 25 to the gears 31 and 37 directly and through the sleeve 32 upon which the gear 31 is carried. 30 The sprocket wheel 46 mounted upon the sleeve 32 drives the shaft 50 and as heretofore described causes the braiding head 10 to be driven. When the device has been operated to the position just described for 35 use in covering a circular type of cable core the gears 29, 41 and 42 associated with the jaw clutch 28 and the gears 35, 43, and 44 associated with the jaw clutch 34, merely run idle upon their axes. 40 In the operation of the speed changing device as heretofore described it will readily be seen that means is provided for simultaneously and selectively changing the actual as well as the relative speeds of operation 45 of the braiding head and the capstan by merely operating the hand lever 64. It will be understood that to give any particular relative change in speeds of operation between the head and capstan upon shifting 50 the jaw clutches in one direction or the other, it is only necessary to provide the desired gearing between the jaw clutches 28 and 34 and the sleeves 32 and 39, respectively. 55 Although the preferred embodiment of the invention herein described is designed for a multi-unit braiding machine, it will be evident that in the application of this speed changing device to a braiding machine comprising 60 a single unit the device would be associated with the shaft corresponding to the shaft 13 which is driven direct by the

motor, thereby not necessitating the use of a jack shaft.

What is claimed is:

1. In a braiding machine, means for braiding material on different shaped cores, means for causing a relative movement between material to be braided and the braiding means, and means for simultaneously changing the speeds of the first and second mentioned means in accordance with the shape of the core being covered with said braided material. 65

2. In a braiding machine, material braiding means, means for receiving the braided material, driving means for said braiding and receiving means, said means comprising a constant speed drive shaft, a plurality of sleeves free to rotate thereon, a clutch device mounted upon said shaft, a second clutch device mounted upon one of said sleeves, gearing associated with said shaft, sleeves and clutches, said shaft and sleeves adapted to be either directly connected together by said clutch devices or through said gearing whereby the relative speeds of operation of said braiding and receiving means may be varied, and means for simultaneously operating said clutches. 75

3. In a braiding machine, means for braiding material on differently shaped cores, means for causing a relative movement between the braided core and the braiding means, and means for changing the speed of the two first mentioned means in accordance with the shape of the core. 90

4. In a braiding machine, material braiding means, means for receiving the braided material, driving means for said braiding and receiving means comprising, a driving shaft, a sprocket wheel mounted on said shaft for driving the braiding means, a gear wheel mounted on said shaft for driving the receiving means, means for driving said sprocket wheel and said gear wheel in unison, and means for driving said sprocket wheel and said gear wheel at different speeds. 100

5. In a braiding machine, material braiding means, means for receiving the braided material, driving means for said braiding and receiving means comprising, a driving shaft, a sprocket wheel mounted on said shaft for driving the braiding means, a gear wheel mounted on said shaft for driving the receiving means, pairs of bevel gears mounted on the shaft, and means for driving the sprocket wheel and gear wheel directly with the shaft or through said bevel gears. 110

In witness whereof, I hereunto subscribe my name this 5th day of August, A. D. 1924.

ROBERT ERNEST McFARLAND.
